ARTICLE-HANDLING SYSTEM

Asa B. Segur, Oak Park, Ill.

Application November 25, 1952, Serial No. 322,389

16 Claims. (Cl. 22—20)

My invention relates to an article-handling system and, more particularly, to a foundry system and method. In the operation of the conventional foundry the molders are required to do much heavy and unpleasant work which reduces their efficiency and output and materially contributes to labor turnover. In a few foundries this heavy and unpleasant work is eliminated by the installation of complicated, expensive and relatively inflexible automatic machinery, but such mechanization is beyond the financial capacities of most foundries and is not adapted to their variegated types of work.

An object of my invention is to provide a new and improved foundry system and method whereby a relatively small capital investment in equipment will eliminate most of the heavy and unpleasant work, greatly increase the output per man, and materially reduce costs of production and labor turnover.

Another object of my invention is to provide a new and improved foundry system and method utilizing a new principle.

Another object of my invention is to provide a new and improved system and method which are not necessarily limited to foundries but may be applied in other fields.

Other objects and advantages will become apparent as the description proceeds.

In the drawings:

Fig. 1 is a diagrammatic top plan view illustrating a layout of two molding floors at the beginning of the molding operation;

Figs. 2, 3, 4, 5, 6, 7, 8 and 9 show successive steps in the molding operation;

Fig. 10 is an enlarged view similar to Fig. 3 and illustrating part of the apparatus for carrying out my molding system;

Fig. 11 is an end elevational view of one of the molding floors shown in Figs. 1 to 10;

Fig. 12 is a partial diagrammatic plan view showing the conveying means for transporting the dumped molds to the points where the castings are removed from the sand and the sand is reconditioned for further use;

Fig. 13 is a side elevational view of the mechanism for dumping the molds;

Fig. 14 is an end view of the mold-carrying tongs, bridge crane, and locating stops;

Fig. 15 is a view showing the pouring of the molds;

Fig. 16 is a view showing the manner in which the tongs are utilized to stack the molds;

Fig. 17 is a view showing the utilization of the tongs to move the jackets and waste from the mold;

Fig. 18 is a side elevational view partly in section of the pouring ladles and supporting crane illustrating the manner for positioning the pouring ladles for different groups of molds;

Fig. 19 is a sectional view taken on the line 19—19 of Fig. 18 showing the detail of the mechanism for positioning the ladles;

2

Fig. 20 is a horizontal sectional view showing positioning of the molds on the tongs;

Fig. 21 is a vertical sectional view taken on the line 21—21 of Fig. 20 showing the positioning guides on the tongs;

Fig. 22 is a side elevational view of an alternative form of bridge crane and tongs;

Fig. 23 is an end view of the crane and tongs of Fig. 22; and

Fig. 24 is an enlarged sectional view of a detail taken on the line 24—24 of Fig. 23.

In the particular embodiment illustrated in Fig. 1, my invention is illustrated as being applied to a foundry area consisting of two molding floors 30 and 32 arranged

15 side-by-side, and, for convenience, each floor may be thought of as being approximately sixteen feet in width, although the floors may be narrower or wider as desired. Each floor is provided with a portable molding machine 34 preferably of the jolt squeeze type and commonly referred to in the trade as a "grasshopper," although any other suitable type of molding machine may be utilized.

20 A table 36 is preferably attached to one side of each molding machine 34 and its associated table 36 is moved 25 lengthwise of its molding floor by a cable 38 attached to a drum 40 (Fig. 12) driven by an electric motor 42, or other suitable source of power. These electric motors are controlled by switch mechanisms on the molding machines in a manner which I shall hereinafter more 30 fully describe.

An elongated pile or windrow 44 of sand extends lengthwise of each molding floor between one edge thereof and the path followed by a molding machine 34. Each windrow 44 is preferably, but not necessarily, interrupted by a gap 46 for a purpose which appears more fully hereinabove. A bridge crane 48 spans both molding floors and has rollers 50 (Fig. 11) at opposite ends 35 engaging tracks 52 extending lengthwise of the molding floors and located adjacent the lateral edges of the two 40 floor area shown in Fig. 1.

The particular molding machine or grasshopper selected for purposes of illustration is shown more fully in Figs. 11, 12 and 14 and comprises a table 54, a movable head 56, and body 58, all carried on a single forward wheel 45 60 and a pair of rear wheels 62. The separate table 36 is independently mounted on two pairs of wheels 64 and is attached at 66 to the molding machine for movement therewith lengthwise of the molding floor.

Stacks of bottom boards 68 are shown upon the table 50 56 and in Fig. 14 the pattern 70 in current use is illustrated as resting upon the head 56. Core supplies 72 and 74 are shown as located in a rack 76 on the separate table 36. A completed mold 78 with the two-section removable metal flask 80 still thereon is shown in Fig. 55 14 on the molding table 54.

60 My novel foundry system is especially adapted for, although not limited to, an operation in which the molds are formed by utilizing metal flasks which are removed from each mold as soon as it is formed and utilized to make the next and each successive mold. The flask with the pattern between the two parts thereof is first placed upon the molding table 54 in upside-down position, the molder shovels sand into the drag or lower (now upper) 65 part of the flask, and the molding machine is operated to compact the sand about the pattern by jolting. The flask is then inverted with a bottom board therebeneath, and sand shoveled into the upper part or cope portion of the flask. A board 82 is then placed on top of the heaping sand, and head 56 pulled forward to engage 70 this board and apply a squeeze to further compact the sand about the pattern. While I have shown the board

82 as separate from the head 56 of the molding machine, in many instances it will be preferable to have this board 82 attached to and carried by the head 56.

The head 56 is then returned to the position shown in Fig. 14, and board 82 removed. The cope section of the mold is now removed and placed upon the separate table 36 while the pattern is extracted and placed in the position indicated by the pattern 70 on the head 56. The cope is then again placed upon the drag and the two parts of the jacket 80 removed as one and laid upon the table 36. The mold is now completed.

In conventional practice the molder would lift the heavy mold from the molding table 54 and place it upon the floor. Since such molds frequently weigh as much as two hundred or two hundred and fifty pounds, this is a tiring and unpleasant operation which consumes much of the molder's energy and time. Features of my invention are the elimination of the stooping associated with placing the mold upon the floor and a reduction to a minimum of the distance which the molder is required to carry the completed mold.

Referring particularly to Figs. 11 and 14, it will be seen that the bridge crane 48 carries two mold supporting racks or tongs 84 each having a length approximately equal to the width of a molding floor. Each pair of tongs 84 is suspended by cables 86 which can be reeled in or payed out by raising mechanism 88 to raise or lower the tongs. Each tong comprises a pair of rectangular open-side frames 90, and each of these side frames is provided with an inturned lower lip 92. The upper ends of the side frames 90 are pivoted at 94 to cross-members 96. The supporting cables 86 are attached to the centers of the cross-members 96.

An arm 98 is rigid with one of the sides 90 and carries a pin 100 movable in a slot in a second arm 102 rigid with the other side 90. A manually operated control bar 104 is pivoted on the pin 100 and has a cam 106 engageable with a cross-member 96 to hold the lips 92 in mold engaging position as shown in Fig. 14. When the lanyard 108 is pulled to rotate the control bar 104 and its cam 106 in a clockwise direction, gravity will swing frames 90 to substantially vertical position thereby separating lips 92 so that the tongs can then be raised or lowered without engaging a mold or other article. On the other hand, when the lanyard 110 is pulled to return the control bar 104 and cam 106 to the position shown in Fig. 14, lips 92 are brought to the mold supporting or article engaging position shown in Figs. 13, 14, 16 and 17.

Instead of placing the completed mold on the floor, the operator simply lifts the bottom board and mold thereon from the molding table, turns around and places the bottom board and mold in the tongs 84 which is suspended in the position shown in Fig. 14 with the lips of the tongs 92 only a slight distance below the molding table 54 so that no stooping is required. In placing the mold in the tongs the molder moves the mold through the open side of the tongs and places the mold in a predetermined position on the lips 92. It is important that the mold be placed in exactly the right position on tongs 84, and to facilitate the proper location of the molds thereon, clips 112 (Figs. 20 and 21) may be affixed to one of the lips 92 for positioning of a mold in abutting relation to one of these clips, as best shown in Fig. 20. As each successive mold is completed, it is moved by the molder from the molding table 54 to his tongs 84 and placed thereon in abutting relationship to one of the clips 112 until the tongs are fully loaded.

When the molders start making molds the molding machines 34 and bridge crane 48 with its two tongs suspended therefrom are in the position shown in Fig. 1. When a molder has completely filled his tongs with molds he lowers the tongs to rest the molds upon the floor. The tongs are then released by spreading the lips 92 and returned to the position shown in Fig. 14. The first row

of molds formed upon the floor by the respective molders are indicated by reference character 114 in Fig. 2.

It is of the greatest importance that each mold in each row be accurately positioned upon its molding floor. I have already pointed out that the positions of the molds upon the tongs are accurately determined by the clips 112 or any other suitable marking means to insure proper spacing of the molds lengthwise of the tongs. I shall now describe the means by which exact positioning of the molds upon the molding floors is effected.

Referring particularly to Figs. 11, 12, 18 and 19, it will be seen that each track 52 is illustrated as being suspended from an overhead beam, or other suitable support by space struts 116, although in many instances it will be preferable to support the track from arms projecting laterally from structural columns located adjacent the molding floor. Transversely extending stops are located at intervals along each track. These stops 118 are given any desired, but exact, spacing and accurately determine different positions of the bridge crane 48 lengthwise of the molding floors. The crane 48 has a stop finger 120 constituting one end of a bellcrank 122 pivoted at 124 to the crane 48. A spring 126 normally holds the lever 122 in engagement with a lug 128 with the finger 120 in stop-engaging position. The finger 120 may be moved to the inactive position shown in dotted lines in Fig. 19 by pulling on a lanyard 130 attached to the other end of the bellcrank 122.

The stops 118 are accurately positioned lengthwise of the tracks 52 so that when the fingers 120 engage the upper sides of these stops, as viewed in Fig. 10, the bridge crane and tongs can assume a definite series of positions lengthwise of the molding floors. The stops 118 and fingers 120 are of predetermined widths measured in a direction lengthwise of the molding floors so that when the fingers 120 engage the other sides of the stops 118 the bridge crane will assume a second accurate series of positions lengthwise of the molding floors. In the drawings I have shown a series of stops 118 on each of the rails 52, but in some instances it will be preferable to use only a single series of stops in lieu of the two series shown.

When the molders start making molds, the bridge crane 48 is in a position like that indicated in Fig. 1 with the fingers 120 engaging predetermined sides of predetermined stops 118 to give the bridge crane an exact location lengthwise of the molding floors. When the tongs are filled with molds and these molds then lowered and placed upon the molding floors to form the first rows 114 (Fig. 2), these rows are accurately positioned lengthwise of the molding floors. The individual molds are also accurately spaced in each row so that, when a row of molds is lowered to the floor, each mold is accurately located both longitudinally and transversely of the molding floor.

A molder utilizes the sand in his windrow 44 beginning at the end adjacent the bridge crane 48, and, as this sand is used up in the molds, it is necessary to advance the molding machine 34 and associated table 36. This may be accomplished by pressing his shovel against the switch 132 (Fig. 14) which controls the motor 42. The control may be such that the molding machine is advanced a predetermined distance each time the switch 132 is operated, but for most purposes it will be sufficient to provide a two-button switch or its equivalent so that by touching one button the molding machine will continue to advance until the other button is touched to stop it. By arranging the buttons or equivalent controls so that they can be engaged either by shovel or by hand, time and efficiency are gained since it is not necessary for the molder to release or pick up his shovel to operate these controls.

As the sand in the windrow is used and the molding machine is advanced, room is made for subsequent rows of molds on the molding floor, and the bridge crane is

advanced from one fixed and exact position to another so that successive rows of molds are deposited on the molding floors with each mold in its proper and exact location. Fig. 2 shows the molding floors with two rows of molds thereon, and a third row in the tongs suspended from the bridge 48. The formation of the molds and the deposition of these molds in rows on the molding floors continues until the first or upper section of each windrow 44 has been exhausted, it being borne in mind that this windrow is made of such size that it corresponds as nearly as possible to the requirements of the successive rows of molds.

When the gaps 46 are reached in the windrows the molding machines are advanced until opposite the ends of the next sections of the windrows, and the bridge crane moved correspondingly. The formation of the molds is then resumed and the molds placed upon the molding floors as before, but leaving gap 134 (Fig. 3) between the two groups of molds 136 and 138 on each molding floor. When all of the sand has been made into molds the molding floors are almost completely covered with molds except for the gaps 134. This condition of the molding floors is best shown in Figs. 3 and 10.

The molds are now ready to be poured but before the actual pouring operation can commence, it is necessary to place jackets and weights on the molds to be poured first. This may be performed either manually or by using the tongs and in a preferred operation jackets and weights will be placed upon the rows 140 and 142 on each molding floor in order to prepare these rows for pouring. A typical jacket is indicated by reference character 144, and a typical weight by reference character 146 (Fig. 15). I shall now describe the apparatus utilized in the pouring operation.

Referring to Fig. 10, it will be seen that I have provided an overhead rail 148 at one side of the two molding floors. Such rail leads to the molding floors from a point adjacent a furnace and is designed to carry ladles filled with molten metal from the furnace to the molding floors. The rail 148 is provided with switches 150 and 152 and a curved end 154 whereby a ladle traveling on the rail 148 may be transferred to a bridge crane spanning the molding floors and carried by the tracks 52 heretofore referred to. Instead of utilizing the bridge crane 48 for this purpose I preferably provide a second bridge crane 156 which I shall hereinafter refer to as a "ladle crane" to distinguish it from the bridge crane 48 which is hereinafter referred to as a "tongs crane." This ladle crane is also provided with releasable fingers 120 for engaging the stops 118, as shown in detail in Figs. 18 and 19.

At the start of the pouring operation the ladle crane 156 is preferably placed in the position shown in Fig. 10, and the switch 152 is in the right-hand position indicated in that figure so that ladles can be moved along the rail 148 and onto the ladle crane 156. A typical ladle 158 is shown in Fig. 18 as being suspended by a cable 160 from an overhead trolley 162 which can be pulled along the rail 148 and crane 156 by hand or in any other suitable manner. It is important that the pouring spout of the ladle be as close as possible to the top of the mold being poured, and the trolley 162 is provided with a chain hoist or other suitable means 164 to raise and lower the cable 160 which supports the ladle.

The molds in row 140 on floor 32 (Fig. 4) are preferably poured first beginning with the right-hand mold and moving in the direction of the arrow in this figure until the row 140 on each floor has been poured. During this pouring operation the position of the ladle crane is accurately determined by engagement of the fingers 120 with the stops 118, and since the molds are accurately positioned on the molding floor, this establishes a predetermined relationship between the ladle and the center

line of the rows of molds. The trolley 162 which carries the ladle is moved lengthwise of the ladle crane by hand as the ladle is shifted from mold to mold.

When the pouring starts the finger 120 engages the 5 right-hand side of a stop 118 as shown in Fig. 18 and the ladle crane remains in this position until the ladle is half empty. The lanyards 130 are then pulled to release the fingers 120, the ladle crane moved to the left, and the lanyards released so that the ladle crane now has its fingers 120 engaging the left-hand side of the same stops 118. This moves the ladle backwardly towards the left, as viewed in Fig. 18, to center the spout more accurately over the center line of the row of molds for pouring the last half of the contents of the ladle. In this Figure 18

15 the ladle is shown at a substantial distance above the top of the mold for purposes of illustrating the different positions of the ladle spout, but it will be understood that in the actual pouring the spout is close to the top of the mold, as shown in Fig. 15.

20 After the row 140 on each molding floor has been poured, the ladle crane is moved out of the way and the tongs crane is moved to a position over the rows 140. The tongs are then lowered to engage the bottom boards of the molds. Next, the tongs are raised and the tongs

25 crane moved to shift the rows 140 of poured molds to the position shown in Fig. 5 where they are again placed in exact position upon the floor as determined by appropriate stops 118. The tongs are now spread to release the lips from beneath the bottom boards and then these lips

30 are brought together to engage angle irons or similar suitable projections 166 provided on the jackets 144. The tongs are now lifted to raise the jackets and weights from the molds in the rows 140. Next, the tongs crane is moved to a position immediately above the rows 163

35 (Fig. 5) and the jackets and weights lowered onto the molds of these rows. Here again the accurate positioning of the tongs crane by the stops 118 and the accurate spacing of the molds transversely and longitudinally of the molding floors makes this possible. The tongs are opened to release the jackets on the molds of rows 163.

The molds in rows 142 are next poured as indicated in Fig. 5, and these rows are then picked up by the tongs and placed on top of the rows 140. This pouring operation

45 proceeds until all of the rows of molds in the groups 136 have been poured and stacked in the center of the molding floor to form the four upper rows shown in Fig. 6. I prefer to stack the poured molds three or four deep in the longitudinal centers of the molding floors and in 50 Fig. 16 I have shown a row of newly poured molds being lowered onto a stack of previously poured molds. Fig. 17 shows the manner in which the tongs remove the jackets and weights from the newly poured molds.

55 When all of the molds in the groups 136 have been poured, the molds in the groups 138 are poured and stacked in the same manner beginning with the mold indicated by reference character 170 in Fig. 5. The pouring and stacking proceeds as indicated in Fig. 6 until all of the molds have been poured and stacked as shown in Fig. 7. The molds are now ready to be dumped and the castings separated from the sand and bottom boards.

60 Dumping tables 172 are now placed in the position shown in Fig. 8 and a pair of skips 174 located adjacent one of these tables. Each skip 174 is adapted to be carried by a hook 176 (Fig. 13) suspended from a trolley of the kind used to carry the ladles and movable along the same rail and ladle bridge. In Fig. 13 the skips 174 are shown as being located immediately adjacent a table 172 and beneath the free edge of the pivoted table top 178 which is held in the position shown by a releasable latch 180. The tongs and tongs crane are now operated to lift a stack of poured molds onto the table top 75 178 with the molds located eccentrically with respect

to the pivot 182. The tongs are opened to release the molds and the tongs moved away. Latch 180 is now released and the stack of molds tilts the table top about its pivot and falls into the skips 174. The bottom boards can be manually removed from the skips at this point or a later point, as desired.

These skips travel in a closed, generally rectangular, path of which the ladle crane forms one side, the track 148 a second side, and a skip rail 184 (Fig. 12) the other two sides. The skips travel in a counterclockwise direction as indicated by the arrow 186 in Fig. 12. The skips with the dumped molds therein are picked up by their respective trolleys and moved about this circuit to the dumping station where the contents of the skips are dumped into an inclined chute 188 leading to a shake-out 190. The shake-out feeds the castings onto a slat conveyor 192. A belt conveyor (not shown) is preferably located beneath the chute 188 and shake-out 190 to catch sand falling therethrough and delivers this sand to a pit 191. An operator knocks the sprues off the castings on the conveyor 192 and sorts the castings into the several receptacles 194. The sprues and other parts to be remelted are delivered to a bin 196.

This dumping of the stacks of poured molds is continued, as indicated in Fig. 9, until all of the molds have been dumped and the skips containing such dumped molds transferred to the skip dumping station 188. The sand which is separated from the castings is delivered to a machine 198 in which this used sand is mixed with fresh sand and otherwise reconditioned for further use. The reconditioned sand is delivered to a loading station 200 where it is placed in skips 174 and carried to the molding floors. The skips with the reconditioned sand pass onto the ladle crane and can be moved lengthwise of the molding floors to form the windrows 44. The ladle crane and its trolley may be provided with interlocks such as the stops 118 and fingers 120 to insure accurate positioning of the windrows.

While I have described my novel system in connection with an operation in which all of the molds are made before the pouring begins, this is not essential as the blocks of molds 136 could be poured while the blocks of molds 138 were being made. It will further be understood that my novel system is likewise adapted for other variations to suit particular needs, and that the particular operation herein described is illustrative only. Furthermore, certain features of my invention, and particularly the positioning means and method, are capable of general application and are not limited to foundry operations.

While the apparatus shown in Figs. 1 to 21 constitutes an effective foundry system for many purposes, variations in the form and type of apparatus used will be desirable under certain conditions. In Figs. 22 to 24 inclusive I have illustrated an alternative form of bridge crane and tongs construction which is particularly advantageous for a foundry making widely variant sizes of molds. This alternative form comprises a bridge crane composed of a pair of spaced but connected I-beams 202 having a pair of centrally located winding drums 204 driven in either direction by electric motors 206. The drums 204 raise and lower a single tongs 208 by means of cables 210 which pass around pulleys 212 rotatably carried by the I-beams 202. The ends of the cables are attached to the tongs 208 by hooks and eyes 214.

The single tongs is as wide as the two molding floors and has two sets of depending arms 216 and 218. An angle iron 220 connects the lower ends of the arms 216 and a second angle iron 222 connects the lower ends of the arms 218. The upper end of each arm 216 is attached to a block 224, and the upper end of each arm 218 is attached to a similar block 226. The blocks 224 and 226 slide between opposed channel members 228 and 230. Screws 232 having reversely threaded portions are

provided to move the blocks 223 and 226 and their depending arms toward and from each other. Each screw 232 is provided with a bevel gear 234 meshing with a second bevel gear 236 on a shaft 238 driven by a motor 240. This motor is of the reversible type so that the screws 232 can be driven in either direction at will.

The bridge crane has rollers 242 for supporting the crane from the track 48, or any other suitable track, and may be moved lengthwise of its track either manually or by power means as desired. I have shown this particular crane as being provided with a pair of arms 244 for pushing or pulling the bridge along its track. One arm is provided with a switch 246 for operating the tongs raising and lowering motors 206 in either direction, and the other arm is provided with a switch 248 for operating the tongs opening and closing motor 240 in either direction. The bridge crane and tongs of this modification is particularly adapted to supporting and transporting molds of widely variant sizes and is equally adapted to carry a row of single molds, as shown in Fig. 22, or a row of stacked molds as indicated in Fig. 23.

From the foregoing description taken in connection with the accompanying drawings it will be apparent that my novel foundry system operates upon a new principle in that the articles worked upon, namely the molds, are accurately positioned in perpendicular directions on a floor or other support by being lowered thereto by gravity by overhead means which may be accurately located in different positions and on which the workpieces are positioned in rows with accurate spacings between the pieces in each row. Particular attention is directed to the relatively simple and inexpensive nature of the apparatus used, and to the fact that my system and method eliminate stooping and other tiring operations, promote efficiency by permitting the workmen to utilize their energies to best advantage, greatly increase output per man, and reduce cost per unit.

The particular procedures which I have described contemplated the making of relatively small molds which are placed upon tongs and lowered thereby to accurate positions on the molding floors. In such molds the cope and drag are assembled at the molding machine and are placed as a unit upon the tongs. With large molds, however, it is customary to assemble the cope and drag after the latter has been placed upon the floor. Where my invention is applied to the making of large molds, the ladle trolley may be utilized to transfer the drag from the point at which it is made to a point exactly above the position which the drag is to occupy on the floor, and then to lower the drag to the floor. The same trolley may then be used to move the cope to a position immediately over the drag and lower the cope onto the drag. In order to make possible accurate and uniform positioning of the trolley in lowering the drag and cope, I preferably provide the bridge crane with stops 118 and the trolley with a stop-engaging finger 120 so that the drags may be accurately located on the foundry floor and the copes easily assembled thereon.

While my invention is particularly adapted to foundries it is not limited to such use but may be applied to any field where it is desired to create accurate assemblies of articles by remote control. It is also to be understood that my invention is not limited to the details shown or described but includes all modifications, variations and equivalents coming within the scope of the following claims.

I claim:

1. In a foundry system of the class described, means for pouring a row of molds comprising a pivotable pouring ladle having a pouring spout, a movable bridge, track means in fixed relationship with a foundry floor and supporting said bridge above the foundry floor, a trolley supporting said ladle from said bridge, an interlock between said track means and bridge for holding said bridge in one

position when said ladle is relatively full, and a second interlock between said track means and bridge for holding said bridge in a second position when said ladle is relatively empty, said interlocks being spaced apart appropriately to compensate for horizontal displacement of said pouring spout resulting from pivoting movement of said ladle to substantially center the pouring spout over the mold as the ladle empties.

2. A foundry system of the class described comprising, a foundry floor, a crane movable lengthwise thereof, a track cooperating with said crane to form a closed path, a skip movable along said closed path, mold dumping means adjacent said path for dumping molds into said skip, a shake-out station adjacent said path to which said skip transfers the dumped molds, a sand reconditioning means adjacent said path for supplying said skip with sand, and means associated with said crane for locating said skip both longitudinally and transversely of said floor to form a windrow of sand thereon.

3. A foundry system comprising a crane movable lengthwise of a foundry floor, means carried by said crane for forming a windrow of sand lengthwise of said floor, a portable molding station, means for advancing said station lengthwise of said floor in close juxtaposition to said windrow, means carried by said crane for receiving a plurality of molds formed at said station, said last-named means being at substantially the height of said station, means for locating said molds accurately on said mold receiving means, means for accurately positioning said crane in different locations lengthwise of said molding floor, means for lowering said mold receiving means to position the molds accurately on said floor, pouring means for said molds, said pouring means including a ladle, and means for accurately positioning said ladle relative to said molds and compensating for tilting of said ladle as the contents of said ladle is transferred to said molds, and means for simultaneously removing a plurality of weights and jackets from certain of said molds and simultaneously placing them upon other molds on said floor.

4. A foundry system comprising a crane movable lengthwise of a foundry floor, means carried by said crane for forming a windrow of sand lengthwise of said floor, a portable molding station, means for advancing said station lengthwise of said floor in close juxtaposition to said windrow, means carried by said crane for receiving a plurality of molds formed at said station, said last-named means being at substantially the height of said station, means for locating said molds accurately on said mold receiving means, means for accurately positioning said crane in different locations lengthwise of said molding floor, means for lowering said mold receiving means to position the molds accurately on said floor, pouring means for said molds, said pouring means including a ladle, and means for accurately positioning said ladle relative to said molds and compensating for tilting of said ladle as the contents of said ladle is transferred to said molds, means for simultaneously removing a plurality of weights and jackets from certain of said molds and simultaneously placing them upon other molds on said floor, means for simultaneously dumping a plurality of said molds, means for simultaneously transferring a plurality of dumped molds to a shake-out station, and means at said station for simultaneously separating the castings from the sand of a plurality of dumped molds.

5. In a foundry system wherein molds are located on a foundry floor with each mold having a predetermined and exact position on said floor with jackets and weights on one group of molds, longitudinally extending track means, a longitudinally movable pick-up means supported by said track means above said floor for simultaneously removing jackets and weights from said one group of molds, a stop in fixed relationship to said floor for locating said pick-up means accurately with respect to said one group of molds, with said pick-up means carrying adjustable stop

means for selective engagement with said stop, means for moving said pick-up means to a position over a second group of molds, a second stop in fixed relationship to said floor for engagement with said adjustable stop means for positioning said pick-up means accurately with respect to said second group of molds, means for lowering said pick-up means to deposit the jackets and weights on the second group of molds, and means for releasing and withdrawing the pick-up means.

10 6. In a foundry system wherein molds are located on a foundry floor with each mold having a predetermined and exact position on said floor with jackets and weights on one group of molds, longitudinally extending track means, a longitudinally movable pick-up means supported by said track means above said floor for simultaneously removing said jackets and weights from said one group of molds, a stop in fixed relationship to said floor for locating said pick-up means accurately with respect to said one group of molds, with said pick-up means carrying adjustable stop means for selective engagement with said stop, means for moving said pick-up means to an intermediate position, a second stop in fixed relationship to said floor for engagement with said adjustable stop means for positioning said pick-up means accurately with respect to said intermediate position, means for lowering said pick-up means to deposit the jackets and weights at said intermediate position in a predetermined fixed relationship where they subsequently can be picked up in this same fixed relationship, and means for releasing and withdrawing the pick-up means.

15 7. In a foundry system wherein molds are located on a foundry floor in longitudinally spaced, identically arranged rows with each mold having a predetermined and exact position on said floor with jackets and weights on one row of molds, means for transferring jackets and weights simultaneously from said one row of molds to another row of molds, said means including a longitudinally movable pick-up means having a transversely extending support surface for receiving a row of jackets and weights in accurate transversely spaced relationship, longitudinally extending track means supporting said pick-up means above the floor, a series of fixed stops in accurate longitudinally spaced relationship to said floor, there being one fixed stop corresponding to each row, and adjustable stop means on said pick-up means selectively cooperating with said fixed stops for accurately positioning said pick-up means with respect to any desired row of molds.

20 8. In a foundry system wherein molds are located on a foundry floor in longitudinally spaced, identically arranged rows, with each mold having a predetermined and exact position on said floor, means for simultaneously picking up one row of molds and stacking it upon another row of molds, said means including a longitudinally movable pick-up means for picking up a row of molds in accurate transversely spaced relationship, longitudinally extending track means supporting said pick-up means above the floor, a series of fixed stops in accurate longitudinally spaced relationship to said floor, there being one fixed stop corresponding to each row, and adjustable stop means on said pick-up means selectively cooperating with said fixed stops for locating said pick-up means in accurate operative position with respect to any desired row of molds.

25 9. In an article-handling system wherein articles are located on a floor in longitudinally spaced, identically arranged rows, with each article having a predetermined and exact position on said floor, means for simultaneously picking up one row of articles and stacking it upon another row of articles, said means including a longitudinally movable pick-up means for picking up a row of articles in accurate transversely spaced relationship, longitudinally extending track means supporting said pick-up means above the floor, a series of fixed stops in accurate longitudinally spaced relationship to said floor,

there being one fixed stop corresponding to each row, and adjustable stop means on said pick-up means selectively cooperating with said fixed stops for locating said pick-up means in accurate operative position with respect to any desired row of articles.

10. In a foundry system wherein molds are located on a foundry floor with each mold having a predetermined and exact position on said floor, a first stop in fixed relationship to said floor adjacent one group of molds on said floor and a second stop in fixed relationship to said floor adjacent another group of molds on said floor, said groups of molds being identical in number and spacing, and said stops each being arranged identically in relation to its group, pick-up means for simultaneously picking up one of said groups of molds, said pick-up means including stop means cooperating with said first stop for accurately locating said pick-up means adjacent said first-mentioned group, means for moving said pick-up means to a position over the second-mentioned group, said stop means of said pick-up means cooperating with said second stop for positioning said pick-up means accurately with respect to said second-mentioned group, and means for lowering said pick-up means to stack said first-mentioned group on said second-mentioned group.

11. A foundry system for handling molds a row at a time comprising means for depositing molds in longitudinally spaced rows on a foundry floor so that each mold has a predetermined and exact position on said floor, said means including a longitudinally movable crane for receiving a row of molds in accurately transversely spaced relationship, longitudinally extending track means in fixed relationship with the foundry floor and supporting said crane above the floor, a series of fixed stops in accurate longitudinally spaced relationship to said floor, and stop means on said crane cooperating individually with said last-named stops and accurately positioning said crane for depositing rows of molds on said floor in accurate longitudinally spaced rows; and means for pouring a row of molds, said last-named means comprising a longitudinally movable ladle crane supported above the floor on said track means, a pivotable pouring ladle, a transversely movable trolley supporting said ladle from said ladle crane, and stop means on said ladle crane cooperating individually with said fixed stops for accurately positioning said ladle crane with respect to any desired row of molds.

12. The system of claim 11 wherein the first-mentioned crane has a mold-supporting surface carrying a series of stops in transversely spaced relationship thereon for receiving a row of molds in accurate transversely spaced relationship.

13. A foundry system for handling molds a row at a time comprising means for depositing molds in longitudinally spaced rows on a foundry floor so that each mold has a predetermined and exact position on said floor, said means including a longitudinally movable crane supported above said floor for receiving a row of molds in accurately transversely spaced relationship, a series of fixed stops in accurate longitudinally spaced relationship to said floor, and stop means on said crane cooperating individually with said last-named stops and accurately positioning said crane for depositing rows of molds on said floor in accurate longitudinally spaced rows; and means for pouring a row of molds, said last-named means comprising a longitudinally movable ladle crane supported above the floor, a pivotable pouring ladle, a transversely movable trolley supporting said ladle from said ladle crane, and stop means on said ladle crane cooperating individually with said fixed stops for accurately positioning said ladle crane with respect to any desired row of molds.

14. In a foundry system that includes a crane movable longitudinally over a foundry floor for picking up and depositing accurately spaced molds a row at a time, a series of accurately longitudinally spaced stops in fixed relation to said floor, and stop means on said crane co-

operating with said stops for accurately locating said crane; the method of handling molds comprising depositing molds on the foundry floor in longitudinally spaced identical rows of transversely spaced molds by means of said crane, with each row in identical relation with a corresponding one of said fixed stops, pouring a plurality of rows of molds, positioning said crane longitudinally by engaging said stop means with one of said stops corresponding to one of the poured rows to pick up said one poured row, and positioning said crane longitudinally by engaging said stop means with one of said stops corresponding to another poured row to stack said one poured row thereon.

15. In a foundry system that includes a crane movable longitudinally over a foundry floor for picking up and depositing accurately spaced jackets and weights a row at a time, a series of accurately longitudinally spaced stops in fixed relation to said floor, and stop means on said crane cooperating with said stops for accurately locating said crane; the method comprising depositing molds on a foundry floor in longitudinal spaced identical rows of transversely spaced molds by means of said crane with each row in identical relation with a corresponding one of said fixed stops, depositing jackets and weights on a row of molds, pouring said row, positioning said crane longitudinally by engaging said stop means with the fixed stop corresponding to said poured row to pick up said jackets and weights, and positioning said crane longitudinally by engaging said stop means with a fixed stop corresponding to another row to deposit the jackets and weights thereon.

16. In an article-handling system that includes a crane movable longitudinally over a floor for picking up and depositing accurately spaced articles a row at a time, a series of accurately longitudinally spaced stops in fixed relation to said floor, and stop means on said crane cooperating with said stops for accurately locating said crane; the method of handling articles comprising depositing articles on the floor in longitudinally spaced identical rows of transversely spaced articles by means of said crane, with each row in identical relation with a corresponding one of said fixed stops, positioning said crane longitudinally by engaging said stop means with one of said stops corresponding to one of the rows to pick up said one row, and positioning said crane longitudinally by engaging said stop means with one of said stops corresponding to another row to stack said one row thereon.
